UNITED STATES PATENT OFFICE.

LOUIS HEIBNER, OF RED BLUFF, CALIFORNIA.

DESIGN FOR A CHECK-HOOK.

SPECIFICATION forming part of Design No. 26,889, dated April 13, 1897.

Application filed February 6, 1897. Serial No. 622,362. Term of patent 7 years.

To all whom it may concern:

Be it known that I, LOUIS HEIBNER, of Red Bluff, in the county of Tehama, State of California, have invented and produced a new and 5 original Design for a Check-Hook, of which the following is a full, clear, and exact description.

The leading feature of the design consists in the hook and a member ranging upward 10 across the rear of the hook and above the same and having a projection extending toward the end of the hook.

Figure 1 is a side elevation of a check-hook embodying my new design, and Fig. 2 is a rear 15 elevation.

The design in its entirety comprises a body *a*, flattened at the sides, the forward end of the body being continued into the form of a hook *b*, which curves forwardly from the body 20 and upwardly and then curves or is returned rearwardly and downwardly to a point above the body *a*, having an opening between the end *a'* of the hook *b* and the top of the body *a*. A member *c* rises from between the cheeks *a'* 25 and extends across the open end of the hook

to a point above the end *a'* of said hook and terminates in a knob *c'*. A projection *c''* extends forwardly from the member *c* into a recess in the end *a'*, as seen in the side view, Fig. 1.

Depending from the body *a* is a shank *d*, of which the lower end is given a threaded appearance.

The leading feature of the design consists in the check-hook, open at the rear, and the 35 member extending across the opening of the hook above the end of the latter and having a projection extending forward toward the end of the hook.

Another leading feature of the design is the 40 member *c*, ranging across the open hook as described and having a knob above the forwardly-extending projection.

I claim—

The design for a check-hook herein shown 45 and described.

LOUIS HEIBNER.
